DESK TOP

William James Bargin, Waukegan, Ill.

Application March 29, 1950, Serial No. 8,839

Term of patent 14 years

(Cl. D33—7)

To all whom it may concern:

Be it known that I, William James Bargin, a citizen of the United States of America, residing at Waukegan, in the county of Lake and State of Illinois, have invented a new, original, and ornamental Design for a Desk Top, of which the following is a specification, reference being had to the accompanying drawing, forming a part thereof.

In the drawing:

I claim:

The ornamental design for a desk top, as shown.

WILLIAM JAMES BARGEN.
